UNITED STATES PATENT OFFICE

SAMUEL WELDON, OF PORTLAND, OREGON

NECKTIE

Application filed May 17, 1928. Serial No. 278,438.

This invention relates to improvements in neckties.

The principal object of my invention is to provide a necktie which is unprovided with a band encircling the neck, that may be readily applied and worn with comfort and security of position.

A further object of the invention is to provide a necktie of simple and practical construction which is readily detachable, detachably connected in wearing position, and which will be retained by elastic means to yield itself readily to changes of position for various shapes of collars worn by the wearer.

15 Further objects and advantages of my invention, and objects relating to details of construction of my invention, will be readily apparent in the course of the detailed description to follow.

20 The accompanying drawings illustrate by way of example a preferred form in which my invention may be embodied, wherein:

Figure 1 is a view in front elevation of my invention.

25 Fig. 2 is a view in rear elevation of the same.

Fig. 3 is a fragmentary view partly in side elevation and partly in vertical section of my improved necktie.

30 Fig. 4 is a fragmentary view of the invention broken away to disclose the construction thereof.

Fig. 5 is a detached perspective view of an element of the invention.

35 Referring to said views, the reference numeral 1 indicates an endless wire frame in the general form of the capital letter Y having its stem 2 comprises of a straight sided wire loop and its branches 3 formed of shorter narrower loops with the wire portion 5 therebetween turned upwardly to provide form and fullness to the upper exposed portion of the tie, as will be more fully explained. The wire loop stem 2 is covered by a sheath 6 of relatively light strong fabric within which and on its outer side a pad 7 of suitable thickness and size to round out the body portion of the tie is secured. The branches 3 are covered by a fabric of the same material as that of the exposed portion of the tie.

In building up the tie a tubular under-flap 8 is provided, as shown, which is suitably shaped or tapered within whose upper end the sheath covered stem 2 is inserted to cover the base of the branches 3 and secured to the frame by stitching through the sheath 6. An overflap 10 of similar tubular form to that of the underflap is secured at its upper end, as at 11, to the back of the tie, and is then drawn over the frame between the branches 3, as at 12, and thence overlying the pad 7 drapes over the underflap in the usual manner. A band 13 is drawn about the body of the tie immediately below the branches 3 overlying the pad 7 and is secured in lapped condition at the rear, completing the tie with finished and pleasing appearance. Supporting devices for my improved necktie consist in an elastic tape sewed at one end at the rear of the tie secured under the lower edge of the band 13. Adjacent the opposite end of the elastic tape a snap fastener socket 17 is secured adapted to be connected to a complementary stud 18 secured to the under-flap 8 in spaced relation below the opposite end of the tape. A stud 19 engaging device 20 is formed at one end with an eye 21 adapted to be threaded upon the tape 16 between the fastener element 17 and its secured end. A forked end 22 is formed at the opposite end of the engaging device 20 which is bent over to engage the shank of a collar button 23 from its upper side.

In operation the wearer will first secure the forked end 22 of the collar-button engaging device over the collar-button 23 while the eye 21 of the device is slipped along the elastic tape as far as it may go through its limitations by the fastener element 17. Then the tape is pulled down by its free end which, running through said eye, will pull the tie upwardly to cause the branches 3 to be thrust upwardly under the folded portions of the collar. The wearer may then secure the fastener elements 17 and 18 together by stretching the tape slightly and thereby exerting a slight tension to press the tie upwardly against the collar and firmly securing it in position where it will remain reliably against displacement.

Having described my invention, what I claim, is:

1. A necktie comprising a Y-shaped wire form including a looped stem and branched loops at its upper end, a fabric sheath about said stem and folded over said form, a tubular fabric underflap enclosing and secured to said sheath, a fabric upper-flap secured to the rear of said form and extending there-over to overlie said underflap, a fabric band extending horizontally about said upper-flap and secured at its opposite ends to the rear of the tie, an elastic tape secured at one end to the rear of said under-flap, a hook-fastener loosely mounted on said tape arranged to be engaged over a collar-button, and a snap fastener for the free end of said tape.
2. A necktie comprising a wire form, a fabric sheath secured over said form, an underflap and an upper-flap secured to said form and sheath in superposed relation, said upperflap being secured to the rear and folded over said form, a horizontally disposed band extending about said flaps and secured to the rear of said form, an elastic tape secured at one end to said underflap and at its opposite end detachably connected through said underflap at the lower end of said form, and a slide-hook mounted on said tape between said connections and adapted for connection with a collar-button.
3. A necktie comprising a wire form, a fabric sheath secured over said form, an under- and an upper-flap secured to said form and sheath in superposed relation, said upper-flap being secured to the rear and folded over said form, a horizontally disposed band extending about said flaps and secured at the rear to said form, an elastic tape secured at one end to said underflap, a slide-hook mounted on said tape and adapted for connection with a collar button, and a snap fastener for the opposite end of said tape having its complementary elements secured at the lower end of the form and to said tape, respectively.
4. A necktie comprising a wire form, a fabric sheath secured over said form, an under- and an upper-flap secured to said form and sheath in superposed relation, said upper-flap being secured to the rear and folded over said form, a horizontally disposed band extending about said flaps and secured at the rear to said form, an elastic tape secured at one end to said under-flap, a slide-hook mounted on said tape and adapted for connection with a collar button, and means to detachably secure the opposite end of said tape at the lower end of the frame.

60 SAMUEL WELDON.
